United States Patent Office

Des. 223,750

Patented June 6, 1972

223,750

SEALING ELEMENT

William J. Berchou, Buffalo, and Freel F. Bryan, Williamsville, N.Y., assignors to Acme Highway Products Corporation, Buffalo, N.Y.

Filed Sept. 10, 1969, Ser. No. 19,098

Term of patent 14 years

Int. Cl. D25—01

U.S. Cl. D13—6

Fig. 1.

Fig. 2.

Fig. 3.

Fig. 4.

Fig. 5.

FIG. 1 is a perspective view of a sealing element, showing our new design;

FIG. 2 is a side elevational view thereof, the opposite side being identical to the side shown;

FIG. 3 is a top plan view thereof;

FIG. 4 is a bottom plan view thereof; and

FIG. 5 is an end elevational view thereof on an enlarged scale, the opposite end being identical to the end shown.

The sealing element is of indefinite length, and is of constant cross-section throughout.

We claim:

The ornamental design for a sealing element, substantially as shown and described.
